Filed Mar. 20, 1972, Ser. No. 233,407

Term of patent 14 years

Int. Cl. D6—06

U.S. Cl. D6—118

FIG. 1

FIG. 2

FIG. 3

FIG. 4

FIG. 5

FIG. 1 is a perspective view of a tie and belt rack showing my new design;

FIG. 2 is a front elevational view thereof;

FIG. 3 is an elevational view of one end thereof;

FIG. 4 is an elevational view of the other end thereof; and

FIG. 5 is a top plan view thereof.

The bottom of the tie and belt rack is substantially the same in appearance as the top. The back of the tie and belt rack is simply a flat rectangular surface.

I claim:

The ornamental design for a tie and belt rack, as shown and described.
